UNITED STATES PATENT OFFICE.

SAMUEL P. WILBUR, OF WILKINSBURG, PENNSYLVANIA, ASSIGNOR TO WESTINGHOUSE ELECTRIC & MANUFACTURING COMPANY, A CORPORATION OF PENNSYLVANIA.

ARC-LAMP.

No. 931,168.

Specification of Letters Patent.

Patented Aug. 17, 1909.

Application filed April 28, 1906. Serial No. 314,206.

To all whom it may concern:

Be it known that I, SAMUEL P. WILBUR, a citizen of the United States, and a resident of Wilkinsburg, in the county of Allegheny 5 and State of Pennsylvania, have invented a new and useful Improvement in Arc-Lamps, of which the following is a specification.

My invention relates to arc lamps and it has for its object to provide a cut-out and 10 feed regulating device therefor which shall enable operation of the lamp upon either a direct or an alternating current circuit, and which shall insure feeding of the electrodes upon the occurrence of a constant predetermined voltage at the arc, regardless of the 15 variations in the amount of current that traverses the circuits of the lamp.

The single figure of the accompanying drawing is a diagrammatic view of the structure and circuits of an arc lamp that embodies my invention.

A pair of electrodes 1 and 2, that are normally in engagement, are adapted to be separated by means of a magnet having a winding 3 connected in series with the electrodes between binding posts 4 and 5 of the lamp. Connected directly between the binding posts 4 and 5 is a comparatively high resistance magnet winding 6 that is mounted upon a 25 projection 7 from a laminated magnetizable core 8, the remainder of which is of substantially E-shape. A movable armature 9 for the magnetizable core 8 carries a terminal piece 10 that is adapted to be brought into 30 engagement with a stationary terminal piece 11 when the armature 9 is attracted by the core 8, for the purpose of establishing a circuit through a resistance 12 and a magnet winding 13 placed upon the middle of the 35 E-shaped portion of the magnet core 8. The high resistance magnet winding 6 becomes sufficiently energized to cause the core 8 to attract the armature 9 when the voltage between the electrodes rises to a predetermined 40 value, and the magnet winding 13 serves to retain the switch in closed position until the electrodes 1 and 2 are again brought into engagement.

When current is first supplied to the lamp, 45 the magnet winding 3 becomes energized and causes separation of the electrodes 1

and 2, an arc being thereby established between them. When the voltage between the electrodes exceeds a predetermined limit the magnet winding 6 becomes sufficiently energized to cause the armature 9 to be raised to effect engagement of the contact terminals 10 and 11. The contact terminals 10 and 11 will be maintained in engagement by the magnet winding 13 until the electrode 1 drops 55 into engagement with electrode 2, whereupon a comparatively low resistance circuit will be established through the magnet winding 3 and the electrodes 1 and 2, when the armature 9 will be released, on account of 60 the reduced magnetizing effects of the windings 6 and 13. Separation of electrodes will then be effected in the usual manner by the magnet winding 3. If, for any reason, the electrodes are not brought into engagement, 65 the magnet winding 13 will remain energized and the lamp will be removed from service without interrupting the circuit from which it is supplied. The magnetizable core 70 8 is laminated and shaped in the manner shown, in order that, when the lamp is supplied with alternating current, heating of the core will not take place and no transformer action will occur between the windings 13 and 6 while the switch contacts 75 10 and 11 are in engagement because little or none of the flux produced by each of the windings 6 and 13 surrounds the other. Obviously, the lamp may also be supplied from a direct current circuit. The voltage at 80 which the magnet winding 6 becomes sufficiently energized to cause feeding of the upper electrode may be regulated within considerable limits by adjusting the weight of the armature 9, by means of suitable 85 counter-weights 14, or otherwise so that changing of the windings for this purpose will be unnecessary in many cases.

I claim as my invention:

1. In an arc lamp, a cut-off device comprising a magnetizable core of substantially E-shape but provided with an auxiliary projecting portion on the side opposite to the three main projections, a magnet winding connected in shunt to the arc and mounted 95 upon the auxiliary projecting portion of the core, a magnet winding mounted upon the 100

central main projection of the core, and a switch for controlling the circuit thereof that is actuated by an armature for the core.

2. In an arc lamp, a cut-out switch for establishing a circuit in shunt to the arc, an operating magnet winding therefor permanently connected in shunt to the arc, a magnet winding for maintaining the switch in closed position when the electrodes are sep-

arated, and a magnetizable core upon which 10 the said magnet windings are mounted in non-inductive relation to each other.

In testimony whereof, I have hereunto subscribed my name this 21st day of April, 1906.

SAMUEL P. WILBUR.
